UNITED STATES PATENT OFFICE.

ARTHUR KAHLOW, OF MAYVILLE, WISCONSIN.

DESIGN FOR A RAILROAD-CROSSING LIGHT.

Application filed March 1, 1924. Serial No. 8,792. Term of patent 14 years.

To all whom it may concern:

Be it known that I, ARTHUR KAHLOW, a citizen of the United States, residing at Mayville, in the county of Dodge and State of Wisconsin, have invented a new, original and ornamental Design for Railroad-Crossing Light, of which the following is a specification, reference being had to the accompanying drawing, forming part thereof.

Figure 1 is a front elevation of the signal light.

Figure 2 is a plan view thereof.

Figure 3 is a bottom view.

The essential features of my ornamental

design consists of a railroad crossing light oval in both horizontal and vertical section and having an oval shape open bottom portion surrounded by a bead, and an upwardly projecting attaching lug at its upper side, and having the insignia shown in the drawings.

I claim:

The ornamental design for a railroad crossing light, as shown.

In testimony that I claim the foregoing I have hereunto set my hand at Mayville, in the county of Dodge and State of Wisconsin.

ARTHUR KAHLOW.
